PLEATING CURTAIN CONSTRUCTION

Edward Lepow, New York, N. Y., assignor to
Home Curtain Corporation, Far Rockaway,
N. Y., a corporation of New York

Application July 23, 1945, Serial No. 606,625

5 Claims. (Cl. 160—348)

1

This invention relates generally to curtains and draperies, and more particularly to construction for the production of pleats in the curtain or drapery as hung on a rod or similar support therefor.

Among the objects of the present invention lies the provision of structure of the class described which is simple in character so that the same may operate in a ready and convenient manner. In accordance with the present invention, it is required only that the rod passage of the curtain be penetrated by the rod or similar curtain supporting member, in order to form the desired pleated effect when the curtain is hung. It is not necessary that the rod be woven in and out of a series of openings in a serpentine manner as disclosed in prior art constructions. This time consuming chore, requiring skill, is eliminated, by the present construction.

Another object herein lies in the provision of self-pleating means which does not require metal or rigid parts, so that the present means may be used upon very light fabric curtains, as well as heavy draperies, and the laundering of the curtain is not affected.

Another object herein lies on the provision of curtains or draperies in which the location and general character of the pleats is predetermined, and this predetermination is substantially fool-proof.

Another object herein lies in the provision of pleating structure which is of low cost, both as to parts and assembly, so that the same has a consequent wide distribution and use.

A further object lies in the provision of novel tape element which may be secured to the curtain or drapery panel in a simple manner and which is provided with indentations or openings which predispose the curtain or drapery to the formation of the proper pleats.

These objects and other incidental ends and advantages will more fully appear in the progress of this disclosure and be pointed out in the appended claims.

In the drawings in which similar reference characters designate corresponding parts throughout each embodiment,

Figure 1 is a front elevational view of a curtain or drapery constituting a first embodiment of the invention. In this figure, the panel is in its pleated state, as hung upon a known curtain rod.

Figure 2 is a plan view, on a reduced scale, of a web of material, as cut to provide a plurality of tape elements, with a minimum of waste.

2

Figure 3 is a fragmentary rear elevational view of a curtain panel constructed in accordance with the first embodiment of the invention, as mounted upon a rod, but not constricted so as to produce the pleats.

Figure 4 is a sectional view as seen from the plane 4—4 on Figure 3.

Figure 5 is a sectional view corresponding generally to Figure 4, but showing the position of the parts when the panel is constricted along the rod to produce pleats.

Figure 6 is a view in perspective, as seen from the rear and above, showing the panel in a partially pleated condition on the rod.

15 Figure 7 is an enlarged sectional view, fragmentary, as seen from the plane 7—7 on Figure 3.

Figure 8 is an enlarged fragmentary sectional view as seen from the plane 8—8 on Figure 3.

Figure 9 is a rear elevational view of a second embodiment of the invention.

20 Figure 10 is an enlarged fragmentary vertical sectional view as seen from the plane 10—10 on Figure 9.

Figure 11 is an enlarged fragmentary vertical sectional view as seen from the plane 11—11 on Figure 9.

Figure 12 is a rear perspective view, fragmentary in nature, showing the curtain panel of Figure 9 being threaded on the curtain rod and in 30 the process of having the pleats formed therein.

Figure 13 is a fragmentary rear elevational view of a third embodiment of the invention.

Figure 14 is a fragmentary enlarged front elevational view of the tape element of Figure 13.

35 Turning now to the first embodiment of the invention illustrated in Figures 1 to 8 inclusive, the curtain or drapery panel is indicated by reference character 11, while the complete device is indicated generally by numeral 10. The panel 11 may be composed of any suitable curtain or drapery fabric and may have a top edge 12, a bottom edge 13, vertical side edges 14 and 15. The top edge 12 may be hemmed in a well known manner so that the free edge of the material of

40 which the panel 11 is composed may lie below the edge 12. The free edge 16 is adapted to be engaged by the upper row of stitches 17 as will more fully appear.

The tape element 20 may be composed of any 45 suitable material, preferably slightly stiff, as for example a soft light buckram. It is desirable that the tape element 20 be not deleteriously affected by any cleaning or pressing operations which the panel 11 may withstand. The tape element 20 is preferably coextensive in length

55

with the width of the panel 11, that is to say, between the edges 14 and 15 thereof. The tape element 20 includes a plurality of supporting portions 21 and a plurality of pleating portions 22. The supporting portions are wider than the pleating portions, so that the former have the projections 23 and 24 while the latter have the indentations 25 and 26. The outer longitudinal edges, forming the indentations 25 and 26 need be inwardly displaced with relation to the other longitudinal edges of the projectings 23 and 24, a distance sufficient so that when the rectilinear rows of stitches 17 and 18 are put in place they will serve to anchor the projections 23 and 24 to the curtain panel 11.

While I have shown the supporting portions 21 as being of lengths substantially equal to the pleating portions 22, as seen for example in Figure 3, as will be obvious to those skilled in the art to which the present invention relates, increasing the length of the pleating portions 22 will engage the pleats, and increasing the length of the supporting portions will increase the distance between the pleats.

In order that the vertical edges 14 and 15 of the panel 11 may be properly supported from the rod 30, it is desirable that the tape element 20 be so positioned on the panel 11 that a part of a supporting portion occur at the said edges. The tape element as an article of manufacture may be extended for any desired length, the same being severed to correspond to the width of the panel with which it is associated.

The tape element 20 may be formed by taking a piece of tape of a width equal to the distance between the outer edges of the projectings 23 and 24, and then cutting away sufficient material at opposite edges to form the indentations 25 and 26, or conversely, the tape element may be formed by taking a piece of tape of a width equal to the distance between the outer edges of the indentations 25 and 26 and adding on the material to form the projectings. One advantageous method of forming the tape element 20 is to cut a web of fabric 29 with cuts 31 and 32, so that the projectings on one tape element dove-tail into the corresponding indentations of the tape elements on either side thereof. This is shown in Figure 2 of the accompanying drawings, in which the cuts for producing the indentations in the outermost strips are indicated by the reference characters 33 and 34.

By properly correlating the distance between the outer edges of the projectings 23 and 24 with the distance between the rows of stitches 25 and 26, the tape element 20 may be installed upon the panel 11 as a single operation on a two needle sewing machine.

In an alternate form of construction, the inner or forward surfaces of the projectings 23 and 24 may be provided with adhesive material, such as a thermoplastic adhesive, or thermosetting adhesive, by means of which the said projectings and hence the supporting portions may be connected to the curtain or drapery panel 11. The pleating portions are free of connection, save through the supporting portions, with the curtain or drapery panel 11. While the tape element 20 has been shown and described as being a separate strip of fabric, the lower edge (the free edge seen in Figure 6) may be extended downwardly a distance equal to the width of the tape element and may be slit as shown in Figure 9. The lower edge just referred to is the lower edge of the top hem.

The use of the present invention is extremely simple. The rod may be inserted into either end of the rod passage 40 which is formed by the tape element 20 and the portion 41 of the panel 11 lying forwardly thereof. Because when it is inserted in a straight line of motion, the rod end 42 engages only the rear surface of the portion 41 and the forward surface of the tape element 20, it has a relatively smooth path, and the insertion of the rod is quickly and easily accomplished. The rod need not be woven in and out of a series of spaced openings.

After the rod 30 is in place, the device may appear as seen in Figures 3 and 4. The portions 15 of the panel forming and adjoining the rod passage may now be constricted (see Figure 6), and the supporting portions will tend to lie along the rod, while the tape pleating portions 22 will buckle rearwardly. The portions 50, of the panel 11, lying forwardly of the portions 22 being otherwise disconnected from the rod will buckle forwardly to form the panel pleats.

Turning now the second embodiment of the invention illustrated in Figures 9 to 12 inclusive, for the purpose of avoiding unnecessary repetition, parts corresponding to those of the first embodiment are given the same reference characters with the addition of a single prime suffix.

The second embodiment differs from the first embodiment principally in the fact that the indentations in the tape element of the first embodiment are omitted and longitudinally arranged slits are provided in the tape element 20'. These slits are indicated by reference characters 125 and 126. The portions of the tape element 20' outwardly of the said slits form the panel pleat reinforcing members 152 and 153 which buckle forwardly with the curtain panel in the pleating process.

40 In the second embodiment, the supporting portions 21' are separated by groups of three pleating portions 22', and between the pleating portions 22' in any group there are two smaller or auxiliary supporting portions 121. This arrangement of the parts produces a triple pleated effect. By varying the size and arrangement of the pleating portions 22', the supporting portions 21', and the supporting portions 121, substantially all of the various conventional drapery and curtain pleating 45 arrangements may be obtained.

As seen in Figure 9, additional tape elements 120 and 220 may be provided, the former being in the middle portion of the panel 11', and the latter adjacent the lower edge 13'. When the curtain 55 10' is mounted on a pair of spaced and parallel rods 30' and 230, the pleating effect is obtained at both ends of the curtain. This construction is desirable for doors, and the like where it is customary or desirable to anchor the curtain at both its upper and lower edges.

The tape element 120 and the portions of the panel 11 immediately adjacent may be constricted by a ribbon or strip 130 to produce an hour-glass effect when the upper and lower edges of the 60 curtain panel are supported on rods, or a conventional tie-back effect when only the upper edge of the curtain panel is supported. The tie-back effect thus provided however, will have the pleats hereindescribed, in predetermined positions as contrasted with the haphazard gathering or shirring normally obtained.

Turning now to the third embodiment of the invention illustrated in Figures 13 and 14, again for the purpose of avoiding needless repetition, 75 parts corresponding to the first embodiment are

given the same reference characters with the addition of a double prime suffix.

In accordance with the construction of the third embodiment, the tape element 20" may be of uniform width so that standard tapes or fabric strips may be used as the base of the tape element. At spaced intervals along one edge of the tape element 20" areas of adhesive material 317 are provided, and oppositely, at similarly spaced intervals along the other edge of the tape element, other areas of adhesive material 318 are provided. The lengths of the areas 317 and 318 determine the lengths (along the rod 30") which will be relatively flat, while the spaces longitudinally of the tape element, between the areas 317 or 318 determine the amount of the curtain panel which will form into a pleat when the curtain panel and tape element are constricted along the rod 30". The distance between any opposed pair of adhesive areas 317 and 318 determines the effective width of the rod passage thereat, and should be sufficient to allow ample clearance for the rod. The adhesive material may be of any suitable character, such as a thermoplastic or thermosetting adhesive, so that the tape element may be ironed on by the use of a heated pressing iron.

The operation of the third embodiment is quite similar to the first embodiment, the pleating portions 22" buckling away from the rod at the same time that the portions 50" buckle away in the opposite direction.

I wish it to be understood that I do not desire to be limited to the exact details of construction shown and described, for obvious modifications will occur to a person skilled in the art.

I claim:

1. A tape element, elongated in shape, and having a series of aligned slits longitudinally disposed in said tape element and spaced from one longitudinal edge thereof; said tape element having a second series of aligned slits oppositely disposed and substantially parallel with said first mentioned series of slits.

2. Curtain or drapery construction comprising: a body panel; a tape element having a series of oppositely disposed projections along the longi-

tudinal edges thereof; and means to secure said projections to said panel; said tape element having pleating portions disposed between the separate pairs of projections, said pleating portions being relatively free of connection with the said panel; said tape element and the opposed portions of the panel forming a passage for the reception of a rod; said panel and tape element being constrictable along said rod; said pleating portions of the tape element buckling away from the rod in one direction when the panel and tape element are constricted therealong.

3. Pleating construction of the class described, comprising: a body panel; an elongated tape element; means to intermittently secure one edge of said tape element to said panel; second means to secure the opposite edge of the tape element to the panel, the second means being oppositely arranged with respect to the first mentioned means, thereby forming a rod receiving channel, with portions of the tape element being free of connection with said panel.

4. Curtain construction comprising: a panel; a tape element secured to said panel along the longitudinal edges of the tape; said tape element having a pair of openings adjacent said tape element edges; whereby the portion of the tape element lying between said openings is substantially free of connection with the panel, and may buckle away from the panel when the panel and tape element are constricted laterally of the panel.

5. Curtain construction comprising: a panel; a tape element secured to said panel along the longitudinal edges of the tape element; said tape element having pairs of opposite openings, the openings in each pair being adjacent the respective longitudinal edges of the tape element, the pairs of openings being spaced from each other along the tape element; said tape element and said panel being substantially free of interconnection in the areas between the openings in each pair of openings; whereby when the curtain is laterally constricted with a rod between the tape element and the panel, the tape element and the panel in said areas may buckle away from each other.

EDWARD LEPOW.
